UNITED STATES PATENT OFFICE.

CHARLES S. WOODS, OF INDIANAPOLIS, INDIANA.

WINDOW-VENTILATOR.

1,376,184.

Specification of Letters Patent. Patented Apr. 26, 1921.

Application filed March 22, 1920. Serial No. 367,666.

To all whom it may concern:

Be it known that I, CHARLES S. Woods, a citizen of the United States, and a resident of Indianapolis, county of Marion, and State 5 of Indiana, have invented a certain new and useful Window-Ventilator; and I do hereby declare that the following is a full, clear, and exact description thereof, reference being had to the accompanying drawings, in 10 which like numerals refer to like parts.

The object of this invention is to provide practical ventilating means for windows suitable for hospitals, offices, residences and other use, arranged so that the deflector, 15 which is made of glass, can be carried by the window sash when the ventilator is not in use and thus be relatively out of the way and not shut out the light and yet the deflector may be readily mounted on the 20 window sill and in such association with the window sash as to permit the latter's elevation independently of the deflector.

This construction furnishes all the advantages of the ordinary deflector construction 25 in ventilators and yet permits the deflector to be mounted on the window sash and be elevated with the window sash in mild weather when it is unnecessary to deflect the current of air upward. Also the deflector 30 will be folded on and carried by the window sash when the room is not being used or ventilation is not desired.

The full nature of this invention will be understood from the accompanying drawings 35 and the following description and claims.

In the drawings Figure 1 is an inside elevation of the window equipped with said ventilating means in position of operation, 40 the window sash being open. Fig. 2 is a central vertical section of the lower part thereof. Fig. 3 is a horizontal section of Fig. 1 just above the ventilating mechanism. Fig. 4 is a similar section with the deflector 45 mounted on the window sash. Fig. 5 is a section similar to that shown in Fig. 2 with the deflector mounted on the window sash and the window sash closed.

There is shown herein a window sash 10 50 having an upper sash 11 and a lower sash 12, and window sill 13, said parts being of the usual construction.

A vertical groove 20 is cut in each side of the lower window sash extending from

the bottom of the window sash up as far as 55 desired, herein about half the height of the sash, and in each of said grooves a vertical iron rod 21 is secured. To the lower rail of each window sash a metal arm 22 is secured so as to project inward, and its inner 60 end is turned upward hook like.

An air current deflector is provided consisting of a central glass plate 25, the length of which is less than the width of the window sash, and two end extension plates 26 65 of the same height as the plate 25 but relatively short and placed against the inner face of the plate 25. For the purpose of adjusting the length of the deflector, each of these plates is surrounded by a metal frame 70 27, preferably, but not necessarily. A shoe 30 covers the lower edges of said metal plates, as shown in Fig. 2. It consists of angle iron plates secured to the glass frames and adapted to rest on the window sill. 75 There is a similar short metal holder 31 secured on the upper edges of said plates at their overlapping portions. This shoe 30 and holder 31 are rigidly secured to the central deflector 25, but the extension plates 80 26 slide longitudinally in said holders so that they may be adjusted. The holders 31 are flexibly connected with the rods 21 so as to slide up and down thereon. This flexible connection consists of three metal bars 85 32, 33 and 34 hinged together in succession with oppositely operating hinges. The bar 34 is slidable on the rod 21 while the bar 32 is secured to the holder 31.

When the deflector is in use, as in Figs. 90 1, 2 and 3, the deflector plate is placed in vertical position on the base board and lengthened by the extension 26 so as to overlap and engage the inner faces of the window casing, as seen in Figs. 1 and 3. The 95 deflector is held in vertical position by the flexible connection at the upper edges thereof, as shown in Fig. 2. Then the lower window sash is elevated as shown, or as desired.

When the ventilator is not in use it is folded up and mounted on the window sash, as shown in Figs. 4 and 5. All that is necessary to effect this is to slide toward each other the two end plates 26 so as to make the 105 total deflector of less width than the window sash, as seen in Fig. 4. Then the deflector is mounted upon the arms 22, whereby it is

carried, and the flexible connection at the upper edge of the deflector permits the upper portion of the deflector to be placed against the window sash, whereby it can be held by the hook or latch 40 which is yieldingly mounted in the window sash so as to catch over the top of the deflector after it is folded up in place on the window sash. When in this position the window sash can

10 be elevated, lowered and used the same as if there were no ventilator and the ventilator will not interfere or shut out the light.

The foregoing drawings and description explains the general nature of this invention, 15 but it is understood that the invention is not limited to the particular detailed construction set forth herein for illustrating said invention.

It will be obvious that various constructions 20 other than that shown herein may be used in place of the rods 21, and the connecting bars 32, 33 and 34, such as a bar having eye connections at both ends, slideable in a metal groove secured to the sash. Therefore, it is 25 not desired to limit this invention to these details of construction of which there may be several various types all coöperating in the same manner.

The invention claimed is:

30 1. The combination with a window casing having a sill and a window sash in the casing, of an air deflector extending transversely of the window and flexibly connected with the window sash so that it may be spaced inwardly therefrom and be supported on the window sill and permit the independent opening of the window sash for ventilation, and means for supporting it by and against the window sash when not in use.

40 2. The combination of a window casing having vertical side faces and a window sill, and a window sash, of an air deflector extending transversely of the window and flexibly connected with the window sash so that it may be spaced inwardly therefrom and be supported on the window sill and permit the opening of the window sash for ventilation, said deflector being longitudinally extensible so that when in position for 45 use it may be extended to permit its ends to engage the facing of the window casing at each side and when not in use be shortened so that its length will not exceed the length of the window sash, and means for supporting it when contracted by and against the window sash when not in use.

50 3. The combination with a window casing having a vertical side face and a window sill, and a window sash, of an air deflector extending transversely of the window and flexibly connected at its upper edge with the window sash so that it may be spaced inwardly therefrom and be supported on the window sill and permit the opening of the 55 window sash for ventilation, said deflector

consisting of a central plate of less length than the width of the window sash and extension plate of the same height as the central plate and longitudinally slideable adjacent each end of said central plate for increasing or decreasing the length of the deflector, and means for supporting it when contracted by and against the window sash when not in use.

4. The combination with a window casing 75 having a vertical side face and a window sill, and a window sash, of an air deflector consisting of a central plate the length of which is less than the width of the sash and an extension plate beside each end of the 80 central plate, a shoe secured to the lower edge of the central plate with a parallel groove therein for receiving said extension plates and permitting their sliding movement, a holder secured to the upper edge of 85 the central plate near each end having a parallel groove therein in which the upper edge of the extension plate is slideable, flexible means connecting each of said holders to the window sash arranged so as to permit the 90 vertical movement of the window sash independently of the air deflector, and means for supporting it when contracted by and against the window sash when not in use.

5. The combination with a window casing 95 having a sill, and a window sash having a vertical groove on the inner face of each side thereof, of a bar mounted so as to be slideable in each of said grooves, an air deflector plate adapted to rest on the window sill inside the window sash, a flexible spacing means secured to the upper side of the deflector plate near each end and secured to said bar, and means for supporting said deflector by and against the window sash when 100 not in use.

6. The combination with a window casing having a sill, and a window sash having a vertical groove on the inner face of each side thereof, of a bar mounted so as to be slideable in each of said grooves, an air deflector plate adapted to rest on the window sill inside the window sash, a spacing bar secured to the upper edge of the deflector near its ends and secured to said bar, and means for 110 supporting said deflector by and against the window sash when not in use.

7. The combination with a window casing having a sill, and a window sash in the casing, of an air deflector extending transversely of the window and flexibly connected at its upper edge with the window sash so that it may be spaced inwardly therefrom and supported on the window sill and permit the independent elevation of the window 125 sash for ventilation, an arm extending inwardly from the bottom rail of the sash near each side and having an upwardly turned inner end upon which the deflector plate can be supported by and against the window 130

sash, and means for releasably holding the upper end of the deflector plate against the window sash.

8. The combination with a window casing having a sill, and a window sash, of vertical guide members secured to the sash at each side thereof, an air deflector plate adapted to rest on the window sill, a flexible connect-

ing member secured to the upper edge of the deflector plate near each end, and slideable on said guide members, and means for supporting said deflector by and against the window sash when not in use. 10

In witness whereof, I have hereunto affixed my signature.

CHARLES S. WOODS.
